UNITED STATES PATENT OFFICE.

CLARENCE L. BROWER, OF CHROME, NEW JERSEY.

BOSH-CRANE.

1,098,090.

Specification of Letters Patent. Patented May 26, 1914.

Application filed June 31, 1913. Serial No. 775,005.

To all whom it may concern:

Be it known that I, CLARENCE L. BROWER, a citizen of the United States, residing at Chrome, in the county of Middlesex and State of New Jersey, have invented certain new and useful Improvements in Bosh-Cranes, of which the following is a specification.

Among the objects of this invention is to 10 provide an efficient device for conveying the anodes from the mold or conveyer to the boshes, and for providing means of adjustment between the grappling device and the point where it will pick up the anode and 15 where it will deposit the same.

The various features of novelty and advantage will be brought out more particularly in describing the invention in connection with the drawings and diagrams accompanying this specification.

In the drawings, one practicable embodiment of the invention is illustrated, in which drawings—

Figure 1 is a plan view of various portions 25 of the plant showing the invention in connection therewith. In this view there is illustrated the furnace, the conveyer, the crane, and a plurality of boshes. Fig. 2 is a cross-section of the parts illustrated in Fig. 30 1 taken at about the plane of the line 2—2 in Fig. 1. Fig. 3 is an end elevation of a portion of the trolley, and a cross-section of the trolley bridge, and shows a broken away portion of an anode carried by the 35 crane; Fig. 4 is a side elevation of the trolley and the crane carried thereby; and Fig. 5 is a top plan view of the trolley.

In one method of refining copper, the copper is run in a molten condition from 40 some suitable furnace—a furnace is illustrated herein at 10—into molds for molding the anodes. The molds are illustrated in a continuous rotary conveyer. There is shown a wheel 11 having a series of molds 12 carried thereby into which the molten copper 45 is run and is formed into anodes 13. This conveyer is shown located between the furnace 10 and a plurality of boshes in which the anodes will be quenched before being 50 conveyed to the electrolytic bath.

The boshes are represented at 14, 15 and 55 16; the bosh 15 is shown at one side of the conveyer substantially diametrically opposite the discharge spout 17 of the furnace.

The conveyer will be rotated step by step,

each of the molds 12 will have a sufficient quantity of metal run into it, and the conveyer will then be stepped around to bring the next mold in position. When the molded anodes arrive in the region of the bosh 60 into which they are to be placed, they will be removed from their molds and conveyed to and deposited in the bosh.

Each of the molds is provided with some suitable means for clearing the cast anode. 65 In the present instance a pin 18 passes upwardly through the bottom of the mold, and has an end depending below the mold in position to be engaged by a cam surface 19 adjacent the position where the anode will be removed from the mold. The pin will be caused to rise and thus lift the end of the anode. The outer end of the anode is shown provided with a pair of engaging lugs 20. 70

It is found difficult in practice to always have the molds from which the anodes are to be taken brought to a given working point at the time the crane is ready to act. The crane must be able to do its work at 80 various positions along the path of revolution of the molds. For this reason in engaging the anode, moving it and depositing it in position, a certain amount of flexibility 85 of movement must be provided in the engaging device, and owing to the location and arrangement of the parts the engaging device must move positively to its position to engage the anode, and must become positively positioned before depositing the same 90 in the quenching bath. The invention therefore provides a crane having a grappling device or pick-up with a swivel motion allowing rapid adjustment to be made to accommodate the difference in position between the mold and the bosh that it is desired to cover. As shown in the drawing, the boshes are placed side by side, which naturally will bring them in different positions along the path of revolution of the 95 mold. The boshes are provided with racks on each side having a series of chamfered notches or sockets 21 for receiving the lugs 20 of the anodes. It will be seen that the anode position indicated by these notches in 100 each of the several tanks is at a different angular position from the line of the lugs 20 at any given position in the orbit of the molds, than is the position of these notches 105 in the companion boshes. This presents an 110

other reason for providing the flexibility of movement of the grapple or pickup.

In the illustration there is shown a bridge 22 having wheels 23 running upon tracks 24.

- 5 The bridge is provided with rails 25 for receiving the wheels 26 of the trolley 27. Suitable means will be provided for causing the bridge to traverse the rails 24, and a motor 28 will be provided for causing the trolley to traverse the bridge. There is suspended from the trolley an operator's platform 29. By this means it will be seen that the trolley has two movements, one transversely of the other, so that it may be moved 10 by the resultant of a compound movement. The mechanism for engaging the anodes will move transversely of the plane of this compound movement, and will also have a swiveling motion in a plane parallel with 15 such plane of movement.

There is shown mounted upon the trolley a rigid leg, that is, rigid in that it is held with the trolley for movement in its two movements, and will be practically free from 20 vibration or swinging independently of the carrier or trolley. This leg in the present illustration comprises a tubular shaft 30 which is caused to rotate by means of a feather 31 engaging a guide 32 (presently to be described), and through which guide it is caused to travel. The traverse of the member 30 is effected by a cable 33 connected to the head 34. The cable runs over a pair of drums 35 provided with cable grooves 36. 25 The grooves are shown right and left handed so that the head 34 will not be moved from side to side as the cable is wound and unwound. The head 34 is shown as having a swivel connection with the shaft 30 and is 30 guided in its traverse and held from rotation with the shaft 30 by means of a pair of guide rods 37 passing through guides 38. The guide rods 37 are movable vertically with the shaft 30. Each end of the head is 35 shown provided with a sheave 39 over which the cable 33 passes for permitting the cable to automatically adjust itself should there be more stretch upon one side than upon the other. A too free movement of the cable however is prevented by suitable clamps 40, or friction devices. The rigid leg 30 is controlled in its vertical traverse and supported by a cable and an outrigger construction.

50 The grappling device 41 is shown non-rotatably carried by the shaft 30 and rotatable relatively to the head 34. This grappling device is shown provided with a pair of hooks 42 for engaging the anode lugs 20.

55 The worm wheel 43 is shown fast with the guide 32 for the shaft 30, and the worm wheel is shown meshing with a worm 44 connected by means of a train of gearing with a motor 45. The drums 36 are connected by means of a train of gearing with

a motor 46 mounted upon the trolley. The various motors for actuating the various parts of the apparatus will have their controlling devices conveniently located for the manipulation of the operator while on the platform 29.

The operation of the device is substantially as follows: The conveyor will be caused to present its various molds 12 to the spout 17 of the furnace. After a suitable quantity of metal has been run into the mold while at the position indicated at 120, another mold will be brought into position and the continued movement of the series of molds in their orbit will bring successive molds carrying their cast anodes to the positions 121, 122 and 123, in which positions the anodes are lifted by the pins 18. From either of their positions the crane may carry the anodes to either of the boshes 14, 15 or 16. To do this the bridge 22 will be moved upon the tracks 24 to a position in line with the anode to be lifted, and the trolley will be moved over the anode into such a position that by a swiveling of the head 41 (if necessary), and a downward traverse of the head and shaft 30, the hooks 42 will come into position to engage the lugs 20 which have been raised from the mold by means of pin 18 and cam 19. The head will 25 then be raised to clear the anode 13 from its mold. The trolley will then be given the proper movement by means of its traverse of the bridge, and the bridge of its tracks, to bring the center of the shaft 30 into line 30 with the longitudinal center of the bosh. During this movement the head 41 will be caused to rotate by means of the worm gearing above referred to, and when the anode 13 has been brought to its proper position 35 relatively to a pair of the notches 21, the shaft 30 and connected mechanism will be caused to lower by means of the playing out of the cable 33, and the anode deposited in the bosh. When the anodes are taken 40 from the position indicated at 122, no swiveling of the head will be required; but when taken from positions 121 and 123 the head will be swiveled in opposite directions to bring the hooks into proper engagement 45 with the ears on the anode castings. It may sometimes arise that some difficulty will be experienced in conveying or depositing an anode where desired, and that the revolution of the molds will have brought the anode 50 past its usual point of being taken up, in which case the operator will be able to readily move the grapple into its proper position for engaging the anode and for conveying it and depositing it where desired. 55 The extensible part of the crane is thus seen to be rigid and to be positively moved from one position to another and positively held in such position, and the swiveling motion of the engaging portion of this ex- 60

tensible member is also positively moved and positively held in position.

It will be apparent that the form of the device herein shown and described is illustrative of the invention, and that changes may be made within the scope of the claims without departing from the spirit of the invention, for the purpose of adapting the invention to the exigencies of its use, and 10 that it may be used in other situations than that described, the present showing being one of its many uses.

Having described my invention, I claim:—

1. The combination with a crane trolley, 15 and means for imparting to the same the resultant of a compound movement in a substantially horizontal plane, of a horizontally disposed head, a vertically disposed guide rod carried by each end of such head, longitudinal guides for said rods carried by the trolley, a rigid shaft carried by the central portion of the head, means for rotating the said shaft, a grapple rotatable with the said shaft, and means for raising and lowering the head relatively to the trolley.

2. The combination with a horizontally disposed head, a vertically disposed guide rod carried by each end thereof, and a rigid shaft carried by the central portion of the 20 head, of means for raising and lowering the head, longitudinal guides for the said rods,

means for rotating said shaft, and a grapple rotatable with the said shaft.

3. In a device of the character specified, the combination with a vertically disposed 35 rigid shaft, means for rotating the shaft, a grapple rotatable with the said shaft, vertically disposed guide rods movable vertically with the said shaft, means for guiding said rods and holding the same from rotation 40 with the said shaft, a cable for raising and lowering said shaft, and outrigged sheaves for engaging the cable.

4. In a device of the character specified, 45 the combination with a horizontally disposed head, of a grapple centrally carried thereby, a cable for raising and lowering the head, a pair of drums for actuating the respective ends of said cable, a pair of sheaves carried by the head and disposed upon the 50 respective sides of the grapple connection therewith, said cable passing around the sheaves, and means carried by the head for applying friction to the cable.

In witness whereof, I have hereunto 55 signed my name in the presence of two subscribing witnesses.

CLARENCE L. BROWER.
